[57] **CLAIM**

The ornamental design for a handle for knives, kitchen tools
and gadgets, as shown and described.

DESCRIPTION

FIG. 1 is a side elevational view of a handle for knives,
kitchen tools and gadgets, showing our new design;

FIG. 2 is a top plan view;

FIG. 3 is an elevational view of the opposite side;

FIG. 4 is a bottom plan view;

FIG. 5 is a left end elevational view of FIG. 2; and,

FIG. 6 is a right end elevational view of FIG. 2.

The broken line showings of a turner in FIGS. 1-6 are for
illustrative purposes only and forms no part of the claimed
design.
